LOUNGE CHAIR

Joseph F. Laskowitz, St. Louis, Mo.

Application August 3, 1953, Serial No. 26,246

Term of patent 14 years

(Cl. D15—11)

FIG. 1.

FIG. 2.

FIG. 3.

Fig. 1 is an isometric view of one side of a lounge chair embodying my new design;

Fig. 2 is a front view, and

Fig. 3 is a rear view of the chair shown by Fig. 1.

The side of the chair opposite that shown by Fig. 1 is identical in appearance to that shown by the first figure of drawing.

I claim:

The ornamental design for a lounge chair, substantially as shown and described.
